CLAIM

The ornamental design for a trailer attachable rear wheel and curb illumination device, as shown and described.

DESCRIPTION

FIG. 1 is a front elevated view of a trailer attachable rear wheel and curb illumination device showing my new design.

FIG. 2 is a rear elevated view of the trailer attachable rear wheel and curb illumination device.

FIG. 3 is a side elevated view of the trailer attachable rear wheel and curb illumination device.

FIG. 4 is a top plan view of the trailer attachable rear wheel and curb illumination device; and,

FIG. 5 is a bottom plan view of the trailer attachable rear wheel and curb illumination device.
